UNITED STATES PATENT OFFICE.

JOHN T. HAWKINS, OF TAUNTON, MASSACHUSETTS.

WEB-PERFECTING PRINTING-MACHINE.

SPECIFICATION forming part of Letters Patent No. 332,521, dated December 15, 1885.

Application filed May 11, 1885. Serial No. 165,051. (No model.)

To all whom it may concern:

Be it known that I, JOHN T. HAWKINS, of Taunton, in the county of Bristol and State of Massachusetts, have invented a new and useful Improvement in Web-Perfecting Printing-Machines, which invention is fully set forth and illustrated in the following specification and accompanying drawings.

The object of this invention is to so arrange a rotary sheet-reverser, (such as that described in the specification of the application filed by me February 18, 1884, and bearing the Serial No. 121,083,) in relation to two impression-cylinders—from one to the other of which it transfers a sheet, reversing it during said transfer—and in relation to a type-cylinder, as to dispense with the necessity for conforming the proportions of said impression-cylinders and type-cylinder to those of the sheet-reverser and to its immediate connection to or distance from said cylinder, so that the position and diameter of said sheet-reverser may instead be made to conform in all cases to all conditions imposed by the other named elements.

The invention consists of the parts and combinations of parts as hereinafter described, and set forth in the claims.

In the accompanying drawings, Figure 1 is an outline longitudinal vertical section through such parts of one-half of a machine as are necessary to illustrate the invention, in which the sheets are cut before printing the first side, showing how (by the employment 35 of intermediate wheels of suitable diameter) the sheet-reverser may, while conforming in diameter to the respective diameters of the impression-cylinders, be placed at any position relative to them and the type-cylinder 40 necessary to bring the sheets at the proper times into positions to meet the proper forms. This figure also illustrates the use of the conveying or controlling cylinder for controlling the head of the sheet in this form of machine, 45 as explained and claimed in my application filed February 18, 1884, bearing the Serial No. 121,084. In the case herein set forth, however, the sheets are cut from the web before printing the first side. Fig. 2 is an enlarged 50 view of part of Fig. 1, showing the relative positions of parts of the sheet-reverser in connection with the contiguous elements of the

machine. Figs. 3 to 7, inclusive, show details of the sheet-reverser and its operating mechanism, by means of which said reverser 55 is actuated from any suitably-moving parts of the machine, similar to that fully described in application Serial No. 121,083, above mentioned.

Referring now to Figs. 1 and 2, the several 60 letters therein indicate the respective parts below mentioned. A is the form-cylinder; A' and A'', the forms; B B', impression-cylinders; C C', the sheet-reverser; C' C'', each a series of tape-pulleys with a gear-wheel on the 65 axis, engaging, respectively, gear-wheels on the impression-cylinders B B'; C'', an intermediate gear-wheel engaging the gears on the axes of the tape-pulleys C' and C'' and the gear on the axis of the sheet-reverser C'. C'' are a 70 series of tape-pulleys running loosely on the same axis to which the gear-wheel C' is secured, so that said pulleys may run in a contrary direction to the gear C' and its shaft. H is a cylinder carrying grippers H'. Said cylinder is 75 made double the diameter of the sheet-reverser C', and geared thereto. D D' are cutting-cylinders for severing the sheets from the web as they pass through the machine. V is the roll from which the machine is fed. L L' 80 L'' L''' L'''' L''''' are each a series of tape-pulleys carried upon suitable shafts. L'' is an intermediate gear-wheel engaging similar wheels on D' and L''''' for imparting motion to the latter. A series of three tapes, t, which run in 85 line with the unprinted margins of the sheet, pass, commencing at L'', to the left around L''', around the impression-cylinder B, thence over C' to and slightly around C'', thence around C'', thence around the impression-cylinder B', 90 thence around L to the right-hand side of the machine, where is repeated this or a similar path, returning again to the pulleys L'', it being presumed here that the entire apparatus shown, except the type-cylinder, is duplicated 95 on the other side of the machine, and therefore not necessary to be shown. A series of tapes, t', commencing at C', pass to the left hand around C'', around C', around C', to the point of starting. A series of tapes, t'', commencing at the top of impression-cylinder B, pass around it to the right, thence partly over C'', thence around H to the point of starting. 100 A series of tapes, t'', commencing at the top of

B', pass around it to the right, thence around L', thence over L², thence to the point of starting. A series of tapes, t¹, commencing at the top of L¹, pass to the right, thence around L⁴, thence under and around L⁵, to the point of starting. It will be obvious that in this construction, by varying the proportions of intermediate gears, C' C³ C⁴, and their pulleys, the sheet-reverser C² may be placed in any position relative to the impression-cylinders B and B' and the form-cylinder A necessary to bring the sheets and forms in contact at the proper times. It will also be seen that in this construction the severed sheets will be conveyed through the entire operation of printing without the use of grippers in the impression-cylinders B B', as in the application Serial No. 121,083, above mentioned. Thus the path of the web will be as follows: Coincident with the sheet being cut from the web by the cutting-cylinders D D' the leading end enters in between tapes t¹ at the point of contact of the impression-cylinder B and pulleys L³, remaining between them until reaching the point of contact of impression-cylinder B and pulleys C', whence it passes to C² between tapes t¹ and t², until seized at the tail end by the twin grippers f⁰ of the sheet-reverser C², the head of the sheet having been previously carried partly around H by the grippers H', which seize the head of the sheet at the proper time at the point of contact of the cylinder H and the sheet-reverser C². The grippers H' are made to release the head of the sheet about at the time that the twin grippers f⁰ have made a semi-revolution. After grasping the tail of the sheet and having conveyed the tail of the sheet so as to enter between the tapes t¹ and t², at which point the twin grippers f⁰ release it, it is conveyed by tapes t¹ t² to the point of contact of impression-cylinder B' and pulleys C³, where it enters between tapes t¹ and t³, being thence conveyed by them until it issues from the machine by the pulleys L L', whence it may be conveyed to the delivery apparatus or folder in any desired position.

The positions of the sheet are indicated throughout by broken lines.

Fig. 3 is an elevation, partly in section, of the sheet-reverser, showing broken parts of the main frames A⁰ of the machine, in which frames it is carried and operated, as fully described in application Serial No. 121,083, above mentioned. Fig. 4 is an end view of the right-hand end of Fig. 3, the frame A⁰ of the machine being removed. Fig. 5 is a transverse section enlarged of the gripper-carrier, showing the twin grippers, their shafts, and operating-levers. Fig. 6 is a side elevation on the same enlarged scale of the levers secured to the twin-gripper shafts. Fig. 7 is a view in plan of one end of the twin-gripper shafts, showing the position of the springs which operate to close the twin grippers upon each other.

Referring to said figures, a gear-wheel, f', is

secured to the shaft f², the latter journaled in the frame A⁰, engaging gears C' and the gear on cylinder H. Three or any number of plain wheels, f³, of the same diameter as the pitch-circle of the gear f', are also secured to the shaft f². Journaled in the gear f' and the wheels f³ is a gripper-carrier, f⁴. In the gripper-carrier f⁴ are journaled two gripper-shafts, f⁶. On one end of the gripper-carrier f⁴ is secured a spur-pinion, f⁸. Upon a stud in the gear f' runs an intermediate pinion, f⁹. On the shaft f² runs freely a wide-faced pinion, f¹¹, gearing on one half its face with the intermediate pinion, f⁹. On a short rock-shaft, f¹², journaled in the frames A⁰, is secured, to its inner end, a sector-gear, f¹³, gearing with the other half of the face of the wide-faced pinion f¹¹, and on its outer end a lever (not shown) carrying a roller which engages a cam, as fully described in application Serial No. 121,083, above mentioned. On the pair of twin-gripper shafts f⁶ are secured pairs of twin grippers f⁰, closing upon each other at their points by means of the springs f¹⁷. The hub of each of these twin grippers f⁰ is made so as to form a stop, i, resting on the flat part of the gripper-carrier f⁴, to prevent one of each pair of grippers f⁰ from following the other when either shall be opened, as hereinafter explained. On each twin-gripper shaft, outside of the outer wheel, f⁸, is secured a lever-arm, f¹⁸, each of said arms carrying a roller, f¹⁹. To the frame A⁰ are secured two stationary cams, f²⁰, in position to engage the rollers f¹⁹. As the entire sheet-reverser is rotated the sector f¹³, by means of the cam referred to—as shown in Serial No. 121,083, but not shown herein—is given such motion as to bring the gripper-carrier f⁴, and with it the twin grippers f⁰, to assume the various positions shown in Fig. 2 in full lines, when delivering the tail of the sheet to and between the tapes t¹ t², into its path to receive its impression upon its second side, and in dotted lines in three other positions, always coming to the several positions shown at those points. At the point shown in full lines, Fig. 2, one of the cams f²⁰ is about to open one of the twin grippers f⁰, allowing the sheet to follow the path between the tapes t¹ t². Continuing the rotation of the sheet-reverser in the direction of the arrow, Fig. 2, both rollers f¹⁹, as next seen in dotted lines, are in contact with the cams f²⁰, and the twin grippers f⁰ are both opened away from each other. Continuing to the next position, as shown in dotted lines, Fig. 2, one of the twin grippers f⁰ has returned to the position as limited by the stop i, and the other is held partly open by the action of one of the cams f²⁰ for the reception of the tail of the sheet then passing in its path between tapes t¹ t² after having received its impression on its first side. Thus the sheet enters from the cutting-cylinders D D' between the tapes t¹, receives its first impression, then passes between tapes t¹ t², is conveyed around the sheet-reverser C², seized

at the head by the grippers H' of the controlling-cylinder H , conveyed partly around the latter, meanwhile being seized by the tail by the twin grippers f^o , until the parts assume

5 the position shown in Figs. 1 and 2, with the grippers H' releasing the head of the sheet to drop down, as indicated by dotted lines at S , Fig. 1, at which time the twin grippers f^o are leading the tail end into and between the tapes $t' t^o$; thence it passes between tapes $t' t^o$, receives its impression on the second side, and finally passes from the machine between tapes $t' t^o$ to the folder or other means of delivery.

I do not herein claim the parts illustrated
15 on Sheet 3 of the accompanying drawings, as the same are claimed in my pending application, Serial No. 121,083, filed February 18, 1884.

Having thus fully described my said improvements, as of my invention I claim—

20 1. In a web-perfected printing-machine, in combination with a type or form cylinder, as A , a pair of impression-cylinders, as $B B'$, a rotary sheet-reverser, as C^o , and a series of intermediate gears, as $C' C^o C^o$, whereby the sheets from one impression-cylinder are timed in their paths proper to meet their respective

forms, while the sheet-reverser is maintained of the same diameter as that of the impression-cylinders, substantially as and for the purposes set forth. 30

2. In a web-perfected printing-machine, in combination with a type or form cylinder, as A , a pair of impression-cylinders, as $B B'$, a rotary sheet-reverser, as C^o , a series of intermediate gears, as $C' C^o C^o$, and a sheet-conveying cylinder, as H , whereby the sheet is reversed, its tail becoming its head, substantially as and for the purposes set forth. 35

3. In a web-perfected printing-machine, in combination with a type or form cylinder, as A , a pair of impression-cylinders, as $B B'$, a rotary sheet-reverser, as C^o , a series of intermediate gears, as $C' C^o C^o$, a sheet-conveying cylinder, as H , and a series of conveying-tapes, as $t' t^o t^o t^o$, forming paths for the sheet, whereby it is conveyed through the impressions and to the sheet-reverser without the use of grippers in said impression-cylinders, substantially as and for the purposes set forth. 40 45 50

JOHN T. HAWKINS.
